UNITED STATES PATENT OFFICE.

LE ROY C. LEWIS, OF ST. PAUL, MINNESOTA, ASSIGNOR TO KOEHLER & HINRICH'S COMPANY, OF ST. PAUL, MINNESOTA.

DESIGN FOR A PLATE OR SIMILAR ARTICLE.

47,337.

Specification for Design.

Patented May 11, 1915.

Application filed January 16, 1915. Serial No. 2,771. Term of patent 3½ years.

To all whom it may concern:

Be it known that I, LE ROY C. LEWIS, a citizen of the United States, residing at St. Paul, in the county of Ramsey and State of Minnesota, have invented a new, original, and ornamental Design for a Plate or Similar Article, which design is represented in the accompanying drawing, forming part of this specification.

The figure is a plan view of a plate showing my new design.

I claim:

The ornamental design for a plate or similar article, as shown.

LE ROY C. LEWIS.

Witnesses:

M. C. BADGER,
L. B. BJOSTAD.
